UNITED STATES PATENT OFFICE.

FREDERICK W. WINTER, OF SAN FRANCISCO, CALIFORNIA, ASSIGNOR OF ONE-FOURTH TO GUSTAVE BEHNING, OF NEW YORK, N. Y., AND ONE-FOURTH TO R. GEORGE GREEN AND ONE-FOURTH TO DAVID C. SPENCE, OF SAN FRANCISCO, CALIFORNIA.

PIANO-PLAYER.

No. 856,325

Specification of Letters Patent.

Patented June 11, 1907.

Application filed August 11, 1905. Serial No. 273,810.

To all whom it may concern:

Be it known that I, FREDERICK W. WINTER, a citizen of the United States of America, and a resident of the city and county of San Francisco, in the State of California, have invented a new and useful Piano-Player, of which the following is a specification, reference being had therein to the accompanying drawings.

10 This invention has for its object to provide a pneumatic player that can be placed in and be made a part of any piano of the upright species, without altering the size or design or outward appearance thereof, and which player shall embody the simplest construction consistent with the highest efficiency.

Referring particularly to the drawings, Figure 1 is a vertical transverse sectional view of an upright piano containing this improved player. Fig. 2 is a front elevation of the same, with the case and lower part of the piano broken away. Fig. 3 is a view of the lower front part of the piano, open and showing an exhaust-chest with pump mechanism in section, which is on the line A—A of Fig. 1, looking to the right. Fig. 4 is a full-sized vertical cross section of another exhaust-chest, the under side of which carries and is operatively connected with a set of pneumatics, the view showing one of these pneumatics in side elevation and connected also for engagement with one of the actuating rods of the piano-action. Fig. 5 is a detached face view of the actuating rod shown in the preceding figure, including a stop in front thereof. Fig. 6 is a view similar to Fig. 4, illustrating a modified construction of the exhaust-chest therein shown. Fig. 7 is a detail of a spring guide for valves included in both the constructions represented by Figs. 4 and 6. Fig. 8 is an enlarged view of the key-bed, sectioned as in Fig. 1 but showing a certain lever connected therewith in a different position. Fig. 9 is a partial sectional plan of the construction illustrated in Fig. 3, below the line B—B. Fig. 10 is a horizontal section on the line C—C of Fig. 4, looking down. Fig. 11 is an enlarged longitudinal section of a certain form of valve-seat comprised in the exhaust-chest of either Fig. 4 or Fig. 6.

In these drawings, the numeral 1 designates the outer case of an upright piano of ordinary construction; 2, the key-bed thereof; 3, the key-board; 4, the strings; and 5, the piano-action. No change or modification is contemplated in the structure or arrangement of these parts of the piano, whether already built or not, in order to apply thereto the present invention.

Like other instruments of the same class, this invention also comprises a number of parts that have been long in use and are well known in the art, among which will be mentioned a tracker-board 6, a series of tubes 7 leading from air-passages therein, a music-roll 8, a take-up roll 9, a perforated sheet of music 10 unwinding from 8 to 9 and vice versa, a pneumatic motor 11, and driving mechanism 12 connecting this motor with the two said rolls, so as to rotate them together alternately in opposite directions. These parts may or may not all be of the customary structural design, but as no specific claim is made herein to any one of them, and their several functions are fully understood, no detailed description of them need be given. The tracker-board with its tubes and the music-sheet and rolls therefor are placed centrally in the upper part of the piano-case, where the same are suspended by a light framework 13, as seen in Figs. 1 and 2. The motor is located at one side (Fig. 1) and rests on an extension 14 of this framework.

Two exhaust-chests 15 and 16 are employed in connection with the above-named parts. One of them (15) may be called the primary exhaust-chest and is placed under the key-bed inside the piano-case, while the other (16), which may be termed the secondary exhaust-chest, is located above the key-board, but substantially in the same vertical plane as the said primary. Both lie in horizontal positions longitudinally of the piano-case, the former being suspended from the key-bed by hangers, as 17, and otherwise suitably supported in the case, and the latter resting therein upon blocks 18, or equivalent supports, that extend upwardly from the keyboard.

The air is pumped out of the primary chest 15 by means of ordinary exhausting-feeders

19 and storage bellows 20, secured to the under side of the said chest, and placed side by side in pairs and in a single line in the lower front part of the piano-case (Figs. 1, 2 and 3). A plurality of these exhausting-feeders and storage bellows is provided, first, to permit the use of a pumping apparatus composed of relatively small-sized members, and secondly, to produce a high vacuum in the machine, as this machine is designed to work at a high pressure, compared with the generally reduced dimensions of its constitutive elements. The several feeders and bellows all have direct communication, through a series of apertures 21, with a suction-chamber 22 in the bottom part of the chest 15, and by means of various passages, channels, and pipes connected therewith (and hereafter described), they draw the air from the motor 11, the secondary chest 16 and its pneumatics, and the tracker-board 6, the tubes 7 whereof communicate with the said secondary chest. The feeders are placed between the bellows and adapted to be worked alternately, each by a folding pedal 23. The bellows are preferably made with parallel tops and bottoms and arranged to work in vertical planes, at right angles to the feeders. They are each subjected to the influence of an external spring 24, which is in the form of a spiral and is vertically disposed between the bottom of its respective bellows and the bottom of the piano-case, being connected with both. The connection with the piano-case is made so as to be permanent, whereas that with the bellows is made adjustable, to regulate the tension of the spring. As suggested in Figs. 1 and 3, the adjustment is effected by means of a winged nut 25, adapted to pull up the spring or push it down along a screw-threaded rod 26, depending from the bellows. The arrangement is such that the bellows, urged by their respective springs, open oppositely to the feeders and coact therewith in producing and maintaining a suitable vacuum in the chamber 22.

Communication between the pneumatic motor 11 and the primary chest 15 is established through a pipe 27, whose upper end leads away from the exhaust-chamber of the motor in the known manner, and the lower end of which discharges into a series of connected passages 28, 29, 30, provided in the chest. See Figs. 2, 3, and 9. As there shown, the passage 28 runs vertically through the upper half of the chest, the passage 29 at right angles thereto and inward longitudinally of the chest, and the passage 30 also at right angles to 29 transversely of the chest and outward into a valve-box 31 in front. Through this box 31, the passage 30 may communicate with the aforesaid suction-chamber 22, in either of two ways. Direct communication is had through a lower opening 32, made in the side of the suction-chamber, and indirect communication through an upper passage 33, leading across the chest to an offset 34, in the rear thereof, thence up a vertical passage 35, in the said offset, to an intermediate pneumatic 36, on top of the chest, and from the said pneumatic down through a similar passage 37, and a lateral opening 38, to the suction-chamber, in the rear. The opening 32 is indicated only by a dotted circle, in Fig. 2. As will be observed, its position relatively to the passage 30 is such that it lies directly opposite a shallow portion of the suction-chamber, as the same appears in Fig. 3, on the right-hand side. This opening 32 and the passage 33 thereabove are respectively controlled by spring-pressed slide-valves 39 and 40, one of which bears upon the bottom of the box 31, while the other rides on a track 41, in the upper part of the same box (Figs. 2 and 9). It is understood that the office of the pneumatic 36 is to regulate the flow of air from the motor so as to place and maintain it under favorable conditions for playing. For a similar purpose, the mouth of the passage 33 is contracted and made partly V-shaped, as represented in Fig. 2, so that as the valve 40 is slid off or over it, the impulse from the motor may be varied more or less to suit the tempo, by governing the speed at which the motor should run and unroll the sheet of music. The uncovering of the opening 32, by withdrawal of the valve 39, establishes an unobstructed communication between the suction-chamber and motor-pipe, and causes the motor to run with full force and speed, as is usually required for rerolling the music-sheet.

Three pipes 42, 43, and 44 connect the primary chest 15 with as many chambers 45, 46, and 47 in the secondary chest 16 (Figs. 1, 2, 3, 4, and 10). These are all suction-chambers. The chamber 45 extends the full length of the chest 16, in its front portion, and is reached by the pipe 42 from the left end. Into this chamber is discharged the air brought in by the tubes 7 of the tracker-board, the lower end of each of which enters a vertical passage 48, provided therefor in the central part of the secondary chest, and tapped about midway of its length by a horizontal forwardly-running passage 49, which is partly covered by a plate 50, having a vent-hole 51, opening into the said chamber. The chambers 46 and 47 occupy the rear half of the chest 16, directly back of the chamber 45, and also run longitudinally of the chest. They are coterminous, abutting one against the other and being separated by a partition 52, which stands in that plane of the piano where the bass ends and the treble begins. The chamber 46 is reached by the pipe 43 from the left end, and the chamber 47 by the pipe 44 from the right end. These two chambers are designed to exhaust the air from a

series of pneumatics 53, adapted each to lift one actuating rod of the piano-action, in the manner hereinafter described. The pneumatics 53 all lie parallel in a single row under and across the chest 16, to the bottom of which their top boards are fastened. In this respect particularly the present invention differs from other mechanical players, wherein such pneumatics are much larger and staggered or arranged in tiers one above another.

From the chamber 45 and the thereinto discharging tracker-board tube 7, the air is conveyed down the pipe 42 and enters the primary chest 15 through a vertical passage 54, in the upper part thereof, at the left end; thence it flows inward through a horizontal passage 55, longitudinally of the chest, into a transverse passage 56, and a valve-box 57, from which it is drawn into the suction-chamber 22 through an opening 58, made in the front wall of this chamber (Figs. 2, 3, and 9). The air from the chambers 46 and 47 of the secondary chest is similarly conveyed down the pipes 43 and 44 into valve-boxes 59 and 60, respectively placed over openings 61 and 62, leading into the ends of a channel 63, which runs nearly the entire length of the primary chest, in its top portion. Unobstructed communication between this channel and the suction-chamber 22 may be had through an opening 64, in the front of the chest 15, which opening leads directly from the said channel into the upper half of the valve-box 57, the latter communicating with the said suction-chamber through the under opening 58, before mentioned. Indirect communication is effected through an intermediate pressure-regulating pneumatic 65, located on top of the chest 15, which pneumatic draws the air from the channel 63 through an upper opening 66, and expels it through a vertical passage 67, in an offset 68, in the rear of the chest, registering with the aforesaid transverse passage 56, and the opening 58 within the valve-box 57. See Fig. 1 in addition to Figs. 2, 3 and 9.

Slide-valves 69 and 70 are placed in the boxes 59 and 60 (Figs. 2 and 3) to respectively control the openings 61 and 62, so that, as the playing shall require, both openings may be simultaneously uncovered, or either opening may be stopped at will. It will be understood that, through the use of these valves, communication between the primary exhaust-chest and either of the chambers 46 and 47 of the secondary exhaust-chest can be wholly or partially cut off, thereby operating to shut off either the bass or the treble, or to subdue either.

Similar valves 71 and 72 are provided in the box 57 (Figs. 2 and 9). These rest edge-wise on tracks 73 and 74, and control the openings 58 and 64, respectively. If the lower opening 58 be closed, it will completely

shut off the flow of air from the secondary chest to the pumping apparatus. On the other hand, the partial or total closing of the upper opening 64 merely affects the direct communication between the pumping apparatus and the chambers 46 and 47 of the secondary chest, governing the same as is required for loud or soft playing.

The above-mentioned pneumatics of the secondary exhaust-chest, which hereafter will be called motor or secondary pneumatics, are deflated each in the following manner. It will be observed that the passage 48 (Figs. 1 and 4), which receives the air from the tube 7 is much larger in cross-sectional area than the vent-hole 51, through which the air must pass in order to reach the suction-chamber 45. Hence the air is retarded in its escape, and part of it descends into a horizontal passage 75, leading forwardly from the lower end of the passage 48. From the passage 75, the retarded air rises into a short vertical passage 76, under a diaphragm 77, which it momentarily causes to swell up. This diaphragm is secured over a suitable cavity 78, in the bottom of the suction-chamber 45, and is adapted to reciprocate a vertically-disposed spindle 79, the upper end of which is passed through an upper passage 80, and carries two valves 81 and 82, respectively controlling the ends of this passage. The latter extends from the suction-chamber 45 to an air-chamber 83 directly above, and affords a means of communication between either of them and an obliquely-running horizontal passage 84, according as the valves 81 and 82 are worked. Upon the upper end of the spindle 79 bears a spring 85, which tends to push it down and also acts as a guide for it during its reciprocation. As the spindle 79 ascends, under the impulse of the diaphragm 77, the lower valve 81 becomes seated, thereby closing the suction-chamber 45 to the passages 80 and 84, and the upper valve 82 is unseated, which opens the air-chamber 83 to the same passages.

Then a small quantity of air from the chamber 83, which is open to the atmosphere, flows into the passages 80 and 84, and is allowed to reach a diaphragm 86, in either the chamber 46 or the chamber 47 of the secondary exhaust-chest, according to the location of the tube 7 that leads in the air from the tracker-board and perforated sheet of music. The diaphragm 86 covers a cavity 87, in the front wall of its respective suction-chamber, 46 or 47, and is caused to swell inward by the incoming external air from the chamber 83. This diaphragm has secured centrally to it a valve-spindle 88, which runs horizontally across the suction-chamber, 46 or 47, and thence out through aligned passages 89 and 90, in the rear of the chest 16. The spindle 88 carries a valve 91, lying in a vertical

channel 92, which separates the passages 89 and 90, and extends from a point slightly above the same down to one of the pneumatics 53, communicating with its pneumatic 5 through a suitable aperture, as 93. This channel, it will be noted, is also capable of communicating with the suction-chamber, 46 or 47, and with the atmosphere, through the passages 89 and 90, which are controlled by the 10 interposed valve 91. A spring 94, similar to the spring 85, is arranged to bear upon and guide the outer end of the spindle 88, keeping the valve 91 normally seated against the passage 89 to the suction-chamber, and allowing 15 the external air to enter the channel 92 through the passage 90, and consequently to flow into and inflate the pneumatic. But when the diaphragm 86 moves inward, as above said, the valve 91 is shifted from the 20 passage 89 to the passage 90, and becoming seated against the latter, excludes the outside air from the channel 92, and establishes a communication between the suction-chamber and the channel, which causes a vacuum 25 therein and the deflation of the thereto appertaining pneumatic. The reversal or contrary movement of the movable parts here referred to takes place as soon as the air in the tube 7 and its sublying passages is exhausted 30 into the suction-chamber 45 through the vent 51, when the diaphragm 77 drops, the valve 81 becomes unseated and the valve 82 seated, the air first let into the passage 84 exhausts into the suction-chamber 45, the 35 diaphragm 86 falls back in its cavity, the valve 91 returns from the passage 90 to the passage 89, and the external air being again admitted into the channel 92 reinflates the secondary pneumatic.

40 The successive inflation and deflation of the row of secondary pneumatics obviously cause the reciprocation of their several bottom boards in parallel vertical planes, which is utilized for operating the several actuating 45 rods of the piano-action. To this end, the bottom board of each secondary pneumatic is provided with a rigid arm 95, extending rearwardly therefrom to a point directly in front of one of the said rods, the latter being 50 designated in the drawing by the numeral 96 (Figs. 1, 4 and 5). The outer end of the arm 95 is made to project under a saddle or inverted U-shaped piece 97, secured to the lower end of the rod 96, wherein the arm 55 comes into contact with a cushion or abutment 98, attached to the lower end of a screw-rod 99, that passes through the top of the saddle and carries a similar cushion or abutment 100 at its upper end. The arm, as it 60 rises with its pneumatic, operates to lift the rod 96, through the under cushion 98 and the saddle 97, and thereby sets in motion the hammer of the piano-action which the same rod is designed to actuate. The cushion

100 is carried up at the same time and is arranged to meet a stop 101, secured to the lower end of another vertically-disposed screw-rod 102, passing through a rail 103. This stop serves to throw off or repel the upwardly-moving arm of the pneumatic, 70 through the upper cushion 100 and connected parts, and thus counteracts the tendency of the arm to stay up and of the pneumatic to remain unduly deflated during fast playing, particularly in repeating. The rail 103 is 75 suitably supported in the piano-case in front and transversely of the actuating rods, and of course carries as many stops as there are pneumatics to operate the said rods. The connection between the actuating rods and 80 the arms of the secondary pneumatics, it will be seen, is a loose one, leaving the rods independently operable or free to be raised by manual operation of the key-board in the common manner, as well as by pneumatic 85 action. But although loose, it will be further seen that the connection is such as to prevent any lateral displacement of the secondary pneumatics, since their respective 90 arms are normally confined in the saddles of the actuating rods, which saddles act as guides to these arms in their reciprocatory movements and offset the comparative narrowness of the pneumatics, due to their being grouped in a single row under the secondary 95 exhaust-chest.

Five levers 104, 105, 106, 107, and 108 are employed in the operation of the above-described player, four to slide the valves 39, 40, 69, 70, 71 and 72, and the fifth to work 100 the so-called forte-pedal, or more properly speaking, the damper-controller (Figs. 1, 2, 8 and 9). The lever 104, the first on the right, is connected with both the valves 39 and 71, by rods or links 109 and 110, attached to opposite sides of the same. The lever 105, next on the left, is connected with the valve 40 by a similar rod or link 111. The middle lever 106 connects with both the valves 69 and 70 through the agency of rods 110 112 and 113. The fourth lever 107 (always counting from the right) is connected with the valve 72 by a rod 114. And the fifth and last lever on the left, 108, connects with the said forte-pedal or damper-controller by 115 means of a rod 115, a bell-crank lever 116, and other suitable linkage (not shown). These several levers are arranged vertically under the key-bed inside the piano-case, and are provided at their upper ends, each with 120 a clutch member 117, through which passes a longitudinally-slidable rockshaft 118, loosely fitted within the said clutch member. Each lever is thus suspended from its respective rockshaft, which latter runs transversely of the key-bed, across the under side thereof, and is journaled in pendent brackets 125 or hangers 119 and 120. The rockshaft has

at its rear end a fixed clutch member 121, which is adapted to engage the aforesaid clutch member 117, when drawn forward, and, after such engagement, to oscillate the thereto connected lever, upon the shaft being rocked. A handle 122 is attached to the outer end of each shaft 118, to afford a convenient means of rocking it, the connection therewith being a pivotal one so that when the instrument is about to be used, the several rockshafts can be pulled outward and their respective handles made to stand at right angles to them, just in front of the key-bed, as represented in Figs. 1 and 2, and when the instrument is not in use, the handles may be turned down in line with their respective rockshafts and pushed back with them under the key-bed, as indicated in Fig. 8. For further convenience, a drawer 123 is provided, to the rear end of which the outer ends of the rockshafts are loosely held by straps or clamps 124, and within which the handles may rest when in their recumbent positions. This drawer fits in angular supports or guide-bars 125, secured to the under side of the key-bed forwardly, and as it slides in or out, as the case may be, operates to move the rockshafts, their handles and clutch members, simultaneously in the same direction.

Fig. 6 illustrates a modified construction of the secondary exhaust-chest, which is somewhat different in design from that shown in Fig. 4, but is believed to be capable of achieving the same results. The secondary chest in the said Fig. 6 is indicated by 16^a, and such component parts thereof as are substantially like those previously described, with reference to the said Fig. 4, are likewise indicated by the same numerals, characterized by the exponent ^a. As these parts discharge functions already understood, it is unnecessary to re-enumerate them all here or to locate them, except to point out that the suction-chamber 45^a is above the other suction-chambers of the chest, which are separated by the partition 52^a. The location of these chambers of course determines the location of the several passages leading to and from the same. The diaphragms of Fig. 4 are replaced in Fig. 6 by pneumatics 77^a and 86^a.

Figs 7 and 11 respectively show in detail the spring guide 85 used in connection with each of the valve-spindles 79, 79^a, 88 and 88^a, and the seat provided for each of the valves carried by the same spindles. The spring in each case is a flat spring suitably perforated to let its valve-spindle pass through, and is adapted to be moved outward by a nut or boss 126 on the valve-spindle. The seat consists of a bushing 127, having a conical head 128, against which the thereto-belonging valve (to be made of pliable material)

will impinge, and with which it will make an air-tight joint.

Having now described my invention, what I claim, and desire to secure by Letters Patent of the United States, is:

1. A piano-player comprising a secondary wind-chest, suitable pumping mechanism, an exhaust-chest connected therewith and located transversely of the player below said wind-chest, motor pneumatics lying in a single row across and beneath and all supported directly from and adjacent said wind-chest and operated through the same from the pumping mechanism, a rigid arm extended from each pneumatic, an actuating rod for each of said arms, means on said rod coöperating with said arm, said means embodying a saddle, and a cushioning device, carried by and movably mounted in said saddle and operating in conjunction with said actuating rod, adapted for severally connecting said pneumatics with a piano-action.

2. A piano-player comprising a wind-chest, motor pneumatics disposed in a single horizontal row across the player below the wind-chest and to which their fixed boards are attached and all supported directly therefrom, and operating connections, serving as guides for the pneumatics, a saddle constructed to prevent lateral displacement of the pneumatics and cushioning means coöperating with said saddle.

3. A piano-player comprising a wind-chest, motor pneumatics placed in a single row across the player below said wind-chest and supported therefrom, arms on said pneumatics, actuating rods, means for loosely interconnecting said rods and pneumatics, and for confining said arms whereby the actuating rods are independently operable and the action can be operated either manually or pneumatically, at will, and lateral displacement of the pneumatics prevented.

4. A piano-player comprising actuating rods, and motor pneumatics arranged in a single row below the player and having each a rigid arm extended toward one actuating rod thereof, said rod being provided with a saddle straddling said arm.

5. A piano player comprising actuating rods, motor pneumatics arranged in a single row below the player and each having a rigid arm extended toward one actuating rod thereof, a saddle on said rod straddling said arm, and a cushioning device coöperating with said arm and saddle.

6. A piano player comprising actuating rods, motor pneumatics arranged in a single row below the player and each having a rigid arm extended toward one actuating rod thereof, a saddle on said rod straddling said arm, a cushioning device coöperating with said arm and saddle, adjustable means acting to throw off or repel the pneumatics after

each stroke, said saddle constructed to prevent lateral displacement of the pneumatics.

7. A piano-player comprising actuating rods, pneumatics provided each with an arm 5 for operating one of said rods, a saddle on the rod lying astride said arm, a stop, and cushions above and below said saddle respectively adapted for engagement with said arm and said stop.

8. A piano-player comprising independently operable actuating rods, a row of pneumatics arranged in a single horizontal row in juxtaposition to each other and placed each opposite one of the said actuating rods, arms 15 operatively connecting said pneumatics with said rods, a rail suitably supported across the rods and above the arms, a saddle on each rod lying astride each arm and independently mounted adjustable stops suspended from said rails.

9. A piano-player comprising pneumatics arranged in a horizontal plane, a member rigid with each pneumatic, a vertically movable actuating rod, a member fixed relatively 25 to said movable rod, cushions upon opposite sides of said fixed member, means connecting said cushions and passed through said fixed member, and a stop disposed above and in the path of the uppermost of said cushions to be engaged thereby.

10. A piano-player comprising pneumatics arranged in a horizontal plane, a member rigid with each pneumatic, a vertically movable member for each of said rigid members, 35 a saddle carried thereby, cushions above and below said saddle, a fixed rail, vertically adjustable members carried thereby, and stops on said members in the path of the uppermost of said cushions to be engaged thereby.

11. The combination with a piano, of a piano-player comprising a main exhaust-chest laid longitudinally under the key bed and horizontally inside the piano-case, an 40 action exhaust chest above the keyboard in the same vertical plane with said main chest and communicating therewith, motor pneumatics, each having an arm, a member carrying a saddle straddling said arm, a tracker-board and a pneumatic motor supported in 45 a plane above the action exhaust-chest respectively communicating one with one of said chests, and the other with the other, a perforated music-sheet adapted to be passed before said tracker-board through the agency 50 of said motor, independently operable actuating rods, a loose connection between the same and the motor pneumatics, a cushioning device coöperating with the arms of the pneumatics, and pumping mechanism located below said parts.

12. The combination with a piano, of a piano-player comprising pneumatics, rigid arms extending from said pneumatics for co-

operation with a saddle independent exhaust-chests, one above and the other below said pneumatics, connections between said chests, means for operating the piano action embodying an adjustable cushion device interposed in each of said means, and comprising simultaneously-movable cushions and a saddle interposed between said cushions.

13. A piano-player comprising pneumatics, rigid arms extending from said pneumatics for coöperation with a saddle independent exhaust chests one above and the other below 75 said pneumatics, connections between said chests, actuating rods, and connections between said rods and pneumatics each embodying an adjustable cushion device, and comprising simultaneously-movable cushions 80 and a saddle interposed between said cushions.

14. A piano-player comprising pneumatics, independent exhaust chests, one above and the other below the pneumatics, connections 85 between said chests, actuating rods, and connections between said rods and pneumatics embodying a saddle and a cushion device, a stop coöperating with one side of said cushion device, and means carrying the 90 cushion device, guided in said saddle.

15. A piano-player comprising pneumatics, independent exhaust chests, one above and the other below the pneumatics, connections between said chests, actuating rods, 95 connections between said rods and pneumatics embodying a saddle on the rods, a cushion device and a stop coöperating with said cushion device, cushion-carrying means guided in said saddle, and means for adjusting said stop.

16. A piano-player comprising pneumatics, independent exhaust chests, one above and the other below the pneumatics, connections between said chests, actuating rods, 105 connections between said rods and pneumatics embodying a saddle and a cushion device, a stop coöperating with the cushion device for each rod, and means for adjusting said stops, each independently of the 110 other.

17. A piano-player comprising pneumatics, independent exhaust chests, one above and the other below the pneumatics, connections between said chests, actuating rods, 115 connections between said rods and pneumatics embodying a cushion device, a saddle carried by each rod, stops coöperating with said cushion device, and means for adjusting said stops, each independently of the other, said actuating rods being independently operable, and a carrier for the cushion device, guided in said saddle.

18. A piano-player comprising pneumatics, independent exhaust chests, one above 125 and the other below the pneumatics, connec-

tions between said chest, actuating rods, connections between said rods and pneumatics embodying a cushion device, a saddle carried by each rod, stops coöperating with said cushion device, an adjustable rod for each cushion device held in said saddle, means for adjusting said stops, each independently of the other, said actuating rods being independently operable, and a loose

connection between said rods and the pneumatics.

In testimony whereof I affix my signature in presence of two witnesses.

FREDERICK W. WINTER. [s.]
